UNITED STATES PATENT OFFICE.

PAUL A. LAWIN, OF LONG PRAIRIE, MINNESOTA.

MOLDING APPARATUS.

1,187,072.

Specification of Letters Patent. Patented June 13, 1916.

Application filed January 17, 1912. Serial No. 671,597.

To all whom it may concern:

Be it known that I, PAUL A. LAWIN, a citizen of the United States, residing at Long Prairie, in the county of Todd and State of Minnesota, have invented certain new and useful Improvements in Molding Apparatus, of which the following is a specification.

My invention relates to improvements for making cement brick, floor tiling, etc., its object being particularly to provide an improved form of machine which can be easily and quickly changed to mold different articles as brick, floor tile, shingles, etc., and by which the article being molded may be handled in the most convenient and effective manner.

To this end the invention consists in the features of construction, combination, and arrangement of parts hereinafter described and claimed.

In the accompanying drawings forming part of this specification, Figure 1 is an isometric view of my invention; Fig. 2 is a similar view of a portion in front of the same illustrating the parts held in position; Fig. 3 is a front elevation of the machine; Fig. 4 is a vertical sectional view thereof showing, in dotted lines, the tampers in tamping position; Fig. 5 is a perspective view of an adjustable anchoring bracket forming part of my invention; Fig. 6 is an end elevation of the machine; Fig. 7 is a detail view of one of the tampers; Fig. 8 is a perspective view of actuating cams for the bottom mold plate; Fig. 9 is a detail view of a movable divider forming part of the invention; and Fig. 10 is a similar view of a removable mold plate forming part of my invention.

Referring to the drawings A represents the framework of the machine. Carried by the machine are the horizontal guides 2 with which a delivery hopper frame 3 slidably coöperates through the medium of ears 4 overlapping the guides. The rear half of said delivery hopper framework is formed with a solid top and the front end of the bed plate with a vertical opening constituting a delivery hopper 5. Fixedly supported above the delivery hopper is a supply hopper 6, the supply hopper being secured between the upper ends of arms 7, said arms being supported at their lower ends as by bolts 8 upon the framework. The delivery hopper is reciprocated through the medium of the lever arms 9, said lever arms at their lower

ends being journaled upon a transverse bar 10 supported by the framework and at their upper ends having slot and pin connection 11 with the delivery hopper framework. A 60 suitable handle 12 is arranged in connection with the upper ends of the lever arms 9. Thus by turning the lever arms 9 through the medium of the handle 12 the delivery hopper will be horizontally reciprocated 65 upon the guides 2 for the purpose herein-after particularly pointed out. Having fulcrum support 13 upon the supply hopper supporting bars 7 are the arms 14, said arms at their lower ends having coil spring connection 15 with the transverse bar 10 and at their upper ends being connected by the handle bar 16. Fixedly supported between the lever arms 14 above the supply hopper, through the medium of the transverse rod 17 70 and the brace arms 18, is a plurality of suitably shaped tampers 19. As will be evident by removing the nuts 20 the tamps may be removed and replaced by substitute tampers.

For forming and removing the bricks or 80 other articles being molded by the machine I employ the following mechanism: Having hinge support 21 upon the front of the machine is a cross plate 22 constituting the front side of the mold, said plate being 85 formed with rearwardly extending side arms 23 and with upwardly extending end brackets 24 forming rests for the pallet boards, as hereinafter set forth. The rear side of the mold is formed by a transverse plate 25, 90 said plate being formed with inwardly extending slots 26 through which extend bolts 27 carried by the framework to allow said plate being adjusted forwardly or rearwardly of the machine to adjust the size of 95 the mold. The plate 25 is formed with a forwardly extending bottom wing 28 to form a rest for the bottom mold board. The end of the mold is constituted by the side plates 29 of the framework. 30 indicates a removable bottom plate for the mold, said plate being formed with a plurality of rearwardly extending separated sections 31 constituting the bottom molds for the individual bricks or other articles being molded. The forwardly extending top of the angle shaped front of the mold support is formed with downwardly extending lips 32 to fit over the hinged front plate 22 of the mold. Normally separating the segments of the bottom 100 plate of the mold is a movable division frame 33 shown in detail in Fig. 9, said

frame being formed with a plurality of forwardly extending interspaced vertical walls 34 designed to stand in the mold between the sections of the bottom plate. Said division 5 frame, as shown, is formed with a rearwardly extending flange 35 adapted to extend over the plate 25 carried by the framework, said flange being formed with downwardly extending lips 37 to fit over said 10 cross bar. Supported underneath the mold upon a shaft 38 journaled in the framework of the machine are a plurality of cams 39, said cams standing underneath the segments of the bottom plate and the mold, when said 15 plate is in position, said shaft being adapted to be turned to carry the cams into engagement with the segments of the bottom plate to lift the same and free the molded articles, by means of a pedal 40 having rod connection 20 41 with said cams, said pedal being normally held raised by a coil spring 42 connecting the pedal with the framework of the machine.

In operation, the supply hopper 6 normally stands filled with the material for 25 making the cement brick, tile, shingles, etc. By then swinging the lever arms 11 forwardly the filling hopper 5 will be brought over the molds to fill the same, the tampers 30 then being turned down to tamping position in the mold through the medium of the handle 16. An ordinary pallet board will 35 then be placed upon the molds and the bottom mold board turned upside down through the medium of the arms 23 to deposit the brick or other articles in delivery position upon the board. After the articles have 40 been released from the mold the mold will be turned back into normal position, when one move of the lever arms 11 will again place 45 the delivery hopper over the mold, filling the molds ready for tamping. By having the mold bottoms and division partitions removable, as shown, so as to be interchangeable, the apparatus can in a few seconds be 50 changed from a brick molding machine to a machine for molding floor tile, shingles, etc. Another advantage of my construction is that I am enabled by means of it to mold the 55 brick on the flat side allowing it to be made hollow on one side to give the mortar a

chance to clench. As has been pointed out, the tampers are removably supported between the arms 13 so as to be easily removed and new tampers substituted to coöperate 55 with any changed construction of mold.

I claim as my invention:

1. In a molding apparatus, the combination with a molding frame consisting of stationary ends, a hinged front plate and a 60 fixed back plate, an element hooked over said front plate to swing therewith, and comprising a longitudinal plate forming mold fronts and rearwardly extending sections forming molding bottoms, and an ele- 65 ment hooked over said back plate and comprising a longitudinal plate forming rear mold ends and a plurality of division plates extending forwardly from said longitudinal plate to interfit between said mold bottoms 70 and to lock over said front plate and the element carried thereby.

2. In a molding apparatus, the combination of a mold frame, comprising fixed end plates, a fixed back plate and a hinged front 75 plate, a unitary set of mold bottoms hooked over the upper edge of said front plate and consisting of a longitudinal strip forming front mold ends and a series of mold bottoms extending forwardly from the lower 80 edge of said longitudinal strip, and a removable partition element coacting with said unitary set and consisting of a longitudinal strip hooked over said back plate and a plurality of division plates extending 85 forwardly therefrom to interfit between said mold bottoms.

3. In a molding apparatus, the combination with a mold frame comprising fixed end plates, a back plate and a hinged front plate, 90 of a set of coacting removable bottom plates and division plates carried by said front and back plates, the division plates and bottom plates each being carried in a unitary group which is hooked over the front and back 95 plates.

In testimony whereof I affix my signature in presence of two witnesses.

PAUL A. LAWIN.

Witnesses:

RAYMOND A. LEE,
PAUL HAUSMANN.
